ABSTRACT: A rotary engine having the following construction. A rotor rotating in an elliptic cylinder is provided with four radial slots and a vane is slidably inserted through each of said slots with the root thereof pivotally connected to each apex of a quadrilateral linkage disposed in said cylinder. When the vane rotates while being carried by the rotor, the movement of the pivot point at the root of each vane is so regulated as to draw a common elliptical locus and, as a result, the tips of each vane moves while drawing a common elliptical locus. The inner peripheral surface of the cylinder in sliding engagement with the tip of each vane is shaped in an elliptical configuration conforming to the locus drawn by the tips of the vanes. By constructing as described above, the friction between the tip of each vane and the inner peripheral surface of the cylinder can be minimized and a stable high-speed running of the engine can be obtained.

VANE-TYPE ROTARY ENGINE

BACKGROUND OF THE INVENTION

The present invention relates to a vane-type rotary engine adapted for use as internal combustion engine, fluid motor, fluid pump, gas compressor, etc.

SUMMARY OF THE INVENTION

The present invention provides a vane-type rotary engine which comprises four vanes disposed in an elliptic cylinder with one end thereof pivotally connected to the apices of a rhombic linkage respectively and rotating therein while being carried by a rotor, the rotational locus of the pivot point of each vane being defined by a cam having a cam surface on which a roller coaxial with said pivot point rolls and the configuration of which is so determined that the pivot points of said respective vanes will move along a common pseudoelliptic path, wherefore the outer end surface of each vane draws a locus of a point lying on an extension of the segment connecting a point on said pseudoelliptic path with the axis of rotation of said rotor and spaced from said axis of rotation of the rotor a distance which is the sum of the length of said segment and the length of said vane, and the configuration of the inner peripheral surface of said cylinder being determined in conformance with said locus, whereby the centrifugal force acting on each vane is offset as a tension of the rhombic linkage because said vane is pivotally connected to said rhombic linkage, and hence the roller rolls on said cam in contact therewith at all times with a minimum contacting pressure and the friction between the outer end surface and the inner peripheral surface of the cylinder is reduced to substantially zero; and which, therefore, is simple in construction, free of vibration and adapted for high-speed, high-pressure operation.

The present invention provides a rotary engine which can be used not only as an internal combustion engine but also as a fluid motor, and can also be operated as a fluid pump, a gas compressor, etc., by imparting an input to the drive shaft to discharge pressure fluid, and thus has a very wide range of application.

BRIEF DESCRIPTION OF THE DRAWINGS

FIG. 1 is a diagrammatical illustration of the present invention;

FIGS. 2 and 3 diagrams for explaining the operational principle of the present invention; and

FIGS. 4 to 6 are views illustrating an embodiment of the present invention; in which

FIG. 4 is a front elevational view; and

FIGS. 5 and 6 are vertical cross-sectional views, respectively.

DESCRIPTION OF THE PREFERRED EMBODIMENT

First of all, the principle behind the present invention will be explained with reference to FIG. 1. A rotor 2 driven by a drive shaft 1 is mounted in a cylinder 3 and vanes 8, 9, 10 and 11 are inserted through radial slots 4, 5, 6 and 7 respectively which are formed diametrically of said rotor. The inner ends of the vanes are pivotally connected to the pivotal connections of an equilateral quadrilateral linkage (hereinafter referred to as rhombic linkage) L composed of links 13, 14, 15 and 16, respectively. The opposite links 13, 15 and 14, 16 of the rhombic linkage are respectively connected to each other at their centers by support links 21 and 22 which are loosely mounted at their central portions on the drive shaft 1.

The rhombic linkage L rotates as the rotor 2 is rotated by the drive shaft 1. In this case, if the length of the diagonal of the rhombic linkage contracts twice during one revolution of the rotor 1, due to deformation of said rhombic linkage, each vane makes an outward and inward movements twice diametrically of the rotor and the outer end surface thereof draws an elliptical locus. Therefore, if the expansion and the contrac-

tion of the rhombic linkage is regulated in such a manner that the outer end surface of each vane will draw common locus, and the configuration of the inner peripheral surface of the cylinder is determined in conformance with said common locus, a rotary engine having two working chambers 34 and 35 between the outer peripheral surface of the rotor and the inner peripheral surface of the cylinder can be obtained.

For the outer end surface of each vane to draw the common locus, it is necessary that the pivot point of the inner end of each vane draws a common locus. To this end, rollers 27, 28, 29 and 30 are mounted on pivot pins by which the inner ends of the vanes are pivotally connected to the rhombic linkage respectively, and a cam 31 is mounted on the end plates which has a cam surface to guide each roller in contact therewith at all times, when said roller moves incident to the rotation of the vane, in such a manner that the axis of said roller (the pivot pin of said vane) will draw a common locus.

In the operation of the rotary engine constructed as described above, the centrifugal force acting on each vane is supported as components of force along the rhombic linkage, and these components of force are counteracted by the centrifugal forces acting on the adjacent vanes and offset as a tension of the rhombic linkage. Thus, the friction between the inner peripheral surface of the cylinder and the outer end surface of each vane is reduced to substantially zero. Furthermore, the relative rotation between the drive shaft and the supporting links loosely mounted thereon is decreased and the sliding speed of the vanes in the respective slots in the rotor is substantially lower than the speed of the piston in a piston engine and each vane is stable as it is supported in said slot. Still further, the mechanism is very simple because the reciprocating movement of the vanes in the respective slots is effected merely by the roller-guiding cam, without using a special means.

The common locus drawn by the pivot points of the respective vanes is determined in the following manner: Namely, referring to FIG. 2 which shows various shapes of deformation of the rhombic linkage, the maximum value of the half of the diagonal length ρ of the rhombic linkage is represented by a and the minimum value of the same by b . The rhombic linkage expands and contracts between the values a and b . Considering the supporting links which connect the centers of the opposite links with each other, each of the supporting links makes an angular motion with respect to the center of the rhombic linkage through an angle of $\pm\Delta\theta_0$ on both sides of a line at an angle of 45° to the vertical and horizontal main axes (the perpendicular axial lines connecting the opposite ones of the four slots in the rotor). Each supporting link (the half of the length thereof being represented by r) rotates incident to the rotation of the rotor, with each end thereof moving along a circumference of a radius r . However, since the rhombic linkage is relatively fixed to the rotor, if an angular oscillation of $\pm\Delta\theta_0$ is imparted to the rhombic linkage on each revolution of the rotor, the pivot point of each vane will draw an elliptical locus.

Then, a control mechanism as shown in FIG. 3 is assumed. Suppose that a sun gear S having a radius $2r_0$ is fixedly mounted in concentrical relation to the rotor and a planetary gear P having a radius r_0 rotates in intermeshing engagement with said sun gear S, with the axis thereof being supported on the rotor, as shown in FIG. 3. Since the sun gear and the planetary gear are in relative motion, it is possible to consider that the sun gear is rotated with the axis of the planetary gear being fixed. In this case, the point of projection on the horizontal diameter of the planetary gear of a pin at the outer end of a crank K having a radius R_0 and rotating integrally with said planetary gear, makes a horizontal motion of $\pm R_0$. If a link G is provided extending from the center of the sun gear to pass the point of projection, said link will repeat an angular motion of $\pm\Delta\theta_0$ twice during one revolution of the rotor, on both sides of a neutral point. This link corresponds to the very supporting link of the rhombic linkage of the present invention. In FIG. 3, when the rotor rotates through an angle of Φ , the crank

rotates through an angle of 2Φ and the supporting link is displaced through an angle $\Delta\theta$ from the neutral position. In this case, the following relation is established:

$$R_o \cos 2\Phi = R \tan \Delta\theta \quad (1)$$

θ takes the maximum value $\Delta\theta_0$ when $\Phi=0$ or $\Phi=\pi/2$. Namely,

$$R_o = R \tan \Delta\theta_0 \quad (2)$$

From equations (1) and (2) above,

$$\cos 2\Phi = \frac{\tan \Delta\theta_0}{\tan \Delta\theta} \quad (3)$$

and thus the relation between the rotational angle Φ of the rotor and the angular displacement $\Delta\theta$ of the supporting link from its neutral position is regulated.

On the other hand, when the rhombic linkage is square in shape, the relation of

$$\sqrt{a^2 + b^2} = 2r \quad (4)$$

is established, while when the rhombic linkage is in an intermediate position, the relation of

$$\rho = 2r \cos (45^\circ + \Delta\theta) \quad (5)$$

is established, whereby the value of the half ρ of the diagonal of said rhombic linkage is determined. ρ is a or b when $\Delta\theta$ is equal to $\Delta\theta_0$. Therefore,

$$\rho_{\max} = a = 2r \cos (45^\circ - \Delta\theta_0) \quad (6)$$

$$\rho_{\min} = b = 2r \cos (45^\circ + \Delta\theta_0)$$

and the ratio therebetween is

$$\frac{a}{b} = \frac{\cos (45^\circ - \Delta\theta_0)}{\cos (45^\circ + \Delta\theta_0)} = \frac{\cos \Delta\theta_0 + \sin \Delta\theta_0}{\cos \Delta\theta_0 - \sin \Delta\theta_0} = \frac{1 + \tan \Delta\theta_0}{1 - \tan \Delta\theta_0} \quad (7)$$

From equation (7),

$$\tan \Delta\theta_0 = \frac{\frac{a}{b} - 1}{\frac{a}{b} + 1} \quad (8)$$

From equation (4), the value of b is calculated, considering that the radius of the rotor is l (the length of the vane) + b and the value of a is obtained by using a suitable design value for r . Then, the value of $\Delta\theta_0$ is determined from equation (7) and the angular displacement $\Delta\theta$ of the supporting link, corresponding to the rotational angle Φ of rotor is obtained from equation (1) and further the half ρ of the diagonal length of the rhombic linkage is calculated from equation (5) with respect to the rotational angle Φ of the rotor. Thus, the locus of the pivot point of each vane is determined.

For instance, when $b=30$ mm. and $r=29$ mm., $a=49.64$ mm. Then, when $l=50$ mm., the radius of the rotor is 80 mm., i.e. $l+b=80$ mm., so that the minor and major diameters of the elliptical inner peripheral surface of the cylinder are $2(b+l)=160$ mm. and $2(a+l)=99.64$ mm. respectively. The cam surface of the cam for guiding the rollers mounted on the pivot pins for the respective vanes is shaped to conform with the locus of a point which lies on an extension of the segment connecting a point on the locus described above with the center of the drive shaft and is spaced from said center of the drive shaft a distance which is the sum of the length of said segment and the diameter of said roller, where said cam surface contacts the outside face of each roller; and to conform with the locus of a point which lies on said segment and is spaced from the point on said locus a distance corresponding to the diameter of the roller toward the center of the drive shaft, where the cam surface of the cam contacts the inside face of each roller.

In carrying out the present invention, the above-described link mechanism is constructed as shown in FIG. 4 in which members corresponding to the respective elements shown in FIG. 1 are indicated by same numerals (and so are in the subsequent drawings).

A rotor 2 driven by a drive shaft 1 has four vane guide slots 4, 5, 6 and 7 formed in the cylindrical peripheral wall thereof

radially in diametrical directions. Within the rotor 2 is provided a rhombic linkage L composed of links 13, 14, 15 and 16 of equal length pivotally connected with each other in sequence by pivot pins 17, 18, 19 and 20. The two pairs of the opposite links 13, 15 and 14, 16 are respectively connected with each other by supporting links 21 and 22 which are pivotally connected to the centers of the respective links by pivot pins 23, 25 and 24, 26 and which are loosely mounted on the drive shaft 1 at their central portions. Vanes 8, 9, 10 and 11 of equal length are inserted through the slots 4, 5, 6 and 7 in the rotor 2, with the inner ends thereof pivotally connected to the pivotal connections of the rhombic linkage by the pivot pins respectively.

Rollers 27, 28, 29 and 30 of equal diameter are rotatably mounted on the pivot pins respectively. Further, a cam 31 having a cam surface as above described is mounted on the sideplates to regulate the movement of each roller, rotating incident to the rotation of said rotor, in such a manner that the center of the pivot pin for said roller will draw a common elliptical locus. By constructing as described above, the outer end face of each vane draws a common elliptical locus as described in the explanation of the principle of the invention given previously, and a cylinder having an inner peripheral surface of a configuration conforming to said locus is provided. The tips of the vanes are provided with spring-biased sealing members 81, 91, 101 and 111 respectively for maintaining sealing between the vanes and the inner peripheral surface of the cylinder even when the engine is subjected to shock. When the vane-type rotary engine is used, for example, as internal combustion engine, a fuel-air mixture injected into a working chamber 34 from an intake port 32 is carried therein while being compressed and, after the compressed mixture is ignited and detonated by an ignition means 50, the exhaust gases are discharged from an exhaust port 33 through a working chamber 35. FIG. 5 is a sectional view taken on the line V-V of FIG. 4. The drive shaft 1 is fixed to opposite sidewalls 301 and 302, and the rhombic linkage L₁ of the type shown in FIG. 4 is loosely mounted on the substantially central portion of said drive shaft 1. Further, rhombic linkages L₂, L₃ of the same type are loosely mounted on the drive shaft 1 on both sides of the rhombic linkage L₁. The corresponding ends of the constituent links of the respective linkages are connected with each other by common pivot pins (e.g. pivot pins 17 and 19) and rollers are rotatably mounted on the opposite ends of said pivot pins (in the case of illustration, rollers 271, 272 are mounted on the pivot pin 17 and rollers 291, 292 on the pivot pin 19). The rollers 271 and 291 on one ends of the pivot pins are guided by a cam portion 311 projecting inwardly from the cylinder wall 322, while the rollers 272 and 292 on the other ends of the pivot pins are guided by a cam portion 312 projecting inwardly from another cylinder wall 322. Each of the opposite cam portions 311 and 312 has an elliptical cam surface which enables the center of each pivot pin to draw a common locus as stated previously. Further, each pivot pin (e.g. the pivot pin 17) has the inner end of each vane (e.g. the vane 8) pivotally connected thereto and the opposite side edges of each vane are so shaped as to be held in close contact with the inner surfaces 301 and 302 of the cylinder walls respectively. With the construction described, when each vane rotates incident to the rotation of the rotor 2, each roller rolls on the cam surface while being guided thereby and the rhombic linkages L₁, L₂ and L₃, connected together by the common pivot pins, rotate synchronously while being deformed into the same shape. Therefore, each vane is carried by the rotor with the outer end surface being held in sliding contact with the inner peripheral surface of the cylinder while moving inwardly and outwardly of the rotor through the slot formed in said rotor, incident to the deformation of the linkage. In the embodiment shown, the rhombic linkage L₁ may be omitted but the use of three rhombic linkages is advantageous in increasing the stability of the vanes.

In FIG. 6 there is shown an application of the present invention, in which two rotary machines A and B according to the

present invention are connected with each other side by side, using a common drive shaft, and are used as two-stage compressor by sending a gas, compressed in the rotary machine A, into the rotary machine B to increase the final compression ratio. The linkages L₁, L₂, L₃ and L₄ are of the type shown in FIG. 4 and the constituent links of the respective linkages are pivotably supported by common pivot pins (e.g. pivot pins 17 and 19). Rollers mounted on the opposite ends of the respective pivot pins (e.g. rollers 271, 291 and 272, 292) roll on cams 311 and 312 projecting from the opposite cylinder walls 321 and 322 respectively, while being guided thereby, and thus define the rotational locus of the linkages. In FIG. 6, the members corresponding to the elements shown in FIGS. 4 and 5 are indicated by same numerals and descriptions thereof are omitted.

I claim:

1. A vane-type rotary engine comprising a cylinder, a drive shaft extending through said cylinder, a rotor mounted on said drive shaft to be driven thereby and having four radial slots formed therethrough in the diametrical direction thereof, an equilateral quadrilateral linkage consisting of four links of equal length pivotally connected with each other in sequence

by pivot pins and supporting links each having the opposite ends thereof pivotally connected to the centers of each of the two pairs of the opposite links, said supporting links being loosely mounted on said drive shaft at the central portions thereof, four radial vanes slidably extending through said four slots in the rotor with the inner ends thereof pivotally connected to said pivot pins respectively, rollers rotatably mounted on said pivot pins respectively and an inwardly projecting cam formed on the inner surface of said cylinder and having a cam surface which engages said rollers and regulates the rotation of the same in such a manner that the pivot points of said respective vanes will draw a common locus as said vanes rotate incident to the rotation of said rotor, the configuration of the inner peripheral surface of said cylinder being so selected as to conform to the locus of a point which lies on an extension of the segment connecting a point on said common locus with the axis of rotation of said rotor and is spaced from said axis of rotation a distance which is the sum of the length of said segment and the length of said vane from the pivot point to the outer end surface thereof.
